(57) **CLAIM**

The ornamental design for a cart, as shown and described.

DESCRIPTION

FIG. 1 is a front-right perspective view of a cart according to the claimed design.

FIG. 2 is a bottom-left perspective view of the cart.

FIG. 3 is a front view of the cart.

FIG. 4 is a rear view of the cart.

FIG. 5 is a left side view of the cart.

FIG. 6 is a right side view of the cart.

FIG. 7 is a top view of the cart.

FIG. 8 is a bottom view of the cart.

FIG. 9 is an enlarged view of the enclosed portion in FIG. 1.

FIG. 10 is a cross-sectional view of the cart along line 10-10 in FIG. 6; and,

FIG. 11 is an enlarged view of the enclosed portion in FIG. 10.

The dash-dash broken lines in the drawings illustrate portions of the cart that form no part of the claimed design. The dash-dot broken lines in FIGS. 1, 6, and 9-11 of the drawings showing the enclosed portions and section line form no part of the claimed design.
